FLOW-CONTROL SYSTEM FOR ROTARY-
VANE COMPRESSORS FOR CONDI-
TIONING AIR

Bernard Sidney Massey, Neville Raymond Lloyd Quinn, John Raphael Allen, and Stanley Clifford Warner, Bristol, England, assignors to The Bristol Aeroplane Company Limited, Bristol, England, a British company

Application October 30, 1950, Serial No. 192,846

21 Claims. (Cl. 62—6)

1

This invention concerns control systems for regulating the volume-flow output of rotary-vane compressors, by which are meant centrifugal and axial flow compressors, and relates more particularly to control systems for cabin pressurising plant of which the compressor forms a part.

With compressors of the centrifugal and axial flow type it is found that the compression ratio falls and the compressor becomes less efficient as a compressor as the volume flow increases. As the volume flow is diminished a higher compression ratio is obtained until a point is reached in which operation of the machine becomes unstable with periodic fluctuations of flow and delivery pressure. This condition is generally known as "surge." To obtain a high efficiency it is desirable to operate the compressor under conditions approaching surge but sufficiently far away from these conditions to allow for unavoidable variation in the volume flow.

The object of the present invention is broadly to provide a control system such that the volume flow output of the compressor is automatically regulated and maintained approximately constant. With such automatic control the compressor may be operated close to the surge condition while ensuring that the condition is not reached.

Another object of the present invention is to provide a control system for a cabin pressurising plant which will ensure that the amount of fresh air which is supplied for the passengers and/or crew does not fall below a predetermined minimum and does not rise to a value greater than is reasonably necessary to avoid surging in the compressor, while keeping a selected pressure in the cabin up to a predetermined altitude and running such air conditioning apparatus as may be necessary.

A further object of the present invention is to maintain the temperature and humidity in the cabin within specified limits over a wide range of ambient conditions.

According to the present invention a control system for regulating the output of a centrifugal or axial flow compressor comprises means to vary the mass flow of air passing through the compressor in direct proportion to the absolute delivery pressure of the compressor and in inverse proportion to the square root of the absolute temperature of the delivered air.

According to a feature of the present invention a control system for regulating the output of a centrifugal or axial flow compressor comprises means to regulate the quantity of air enter-

2

ing the compressor, a Venturi system to which the compressor delivers, means responsive to the absolute delivery pressure of the compressor, means responsive to the differential pressure between the inlet and throat of the Venturi system and means controlled by said pressure-responsive means to adjust the air-regulator means to vary the quantity of air passing through the compressor in such a way that the ratio of the Venturi differential pressure to the compressor delivery pressure is maintained constant.

According to another feature of the present invention a control system for regulating the output of a rotary-vane compressor comprises a throttle valve on the intake side of the compressor, a Venturi system on the output side of the compressor, a capsule responsive to the absolute delivery pressure of the compressor, a capsule responsive to the differential pressure between the inlet and the throat of the venturi, a servo system for adjusting the throttle valve and means applying the capsule adjustments to the servo-system whereby the throttle valve is adjusted to vary the quantity of air passing through the compressor in such a way that the ratio of the Venturi differential pressure to the compressor delivery pressure is maintained constant.

A practical application of the present invention will now be described, by way of example only, with reference to the accompanying drawings which show a cabin pressurising plant embodying the present invention.

In the drawings:

Figure 1 is a block diagram illustrating the plant as a whole.

Figure 2 shows the principal parts of the flow control system, partly diagrammatically and with parts cut away to show internal construction.

Figure 3 is a longitudinal section through a fluid pressure actuator and servo device shown in Figure 2.

Figures 4 to 8 inclusive are sections taken along lines 4—4 to 8—8 inclusive in Figure 3.

Figure 9 is a diagram illustrating the characteristics of the compressor.

Referring to Figure 1, an aircraft cabin 1 is supplied with air through a non-return valve 2 by a plant arranged in the wing of the aircraft, the air passing along distribution ducting 3, possibly with the addition of recirculated air, to various parts of the cabin as required, and then being returned to the atmosphere at least partly through a discharge valve 4 which is controlled by a pressure sensitive device 5 of known kind which permits the pressure in the cabin to be

maintained at a desired value or varied according to a desired law in relation to changes of altitude of the aircraft.

The air supply plant comprises a compressor 6 of the rotary vane type (centrifugal or axial flow) driven from an engine 7 of the aircraft through a variable speed gear 8, shown as a two speed gear, though a greater number of speeds may be provided if necessitated by the design and operational characteristics of the plant. The variable speed gear comprises an actuator 9 for selecting "neutral" or "engaged" and an actuator 10 for selecting "low speed" or "high speed." These actuators may, for example, be solenoids operating control valves to admit fluid under pressure to hydraulically operated clutches to carry out the required gear changes. The actuator 9 is connected through a switch 11 for starting and stopping the plant to a mains supply at 12, while the actuator 10 is connected through the plant switch 11 and a speed control switch 13 to the mains supply at 12. The speed control switch 13 is operated by an evacuated capsule 14 responsive to atmospheric pressure, the arrangement being such that at low altitudes the variable speed gear is maintained in the low speed setting, and that when a predetermined altitude is reached a change is made into a higher speed. In the case of a two speed drive for a plant designed to operate up to altitudes of the order of 40,000 ft. above sea level the change may be made, for example, at an altitude of about 22,000 ft. The switch 13 includes a trip or equivalent mechanism whereby contact is made for an upward speed change at an altitude somewhat greater than the mean change-speed altitude and is broken for a downward speed change at an altitude correspondingly below the mean change-speed altitude. This overlap range may be of the order of 1000 ft. and obviates unstable running of the plant when the aircraft is flying at about the change-speed altitude.

The plant also includes the usual air conditioning devices, namely a cooler 15, heater 16, refrigerator 17 and water separator 18. The cooler 15 and the heater 16 are of the heat exchange type in which cold or hot air is passed in heat-exchange relationship with the air flowing to the cabin along the duct 19 from the compressor 6. Control of the cooler and heater is by means of valves 20 and 21 respectively in the cooling and heating air circuits. The refrigerator 17 is of the free-running compressor-expander type with an interposed secondary cooler and is controlled by a valve 22 arranged in a bypass duct 23. The heater, cooler and refrigerator are controlled in progressive sequence by a variable datum thermostat 26 arranged in the cabin, where it may be set by an engineer or steward, and adapted to operate the valves 20, 21 and 22 by means of an actuator 27. As shown in Figure 2, this actuator may be a geared electric motor 28 driving a camshaft 29 carrying three cams 30, 31 and 32 pertaining to the heater, cooler and refrigerator control valves respectively. The refrigerator cam 32 operates the refrigerator by-pass valve 22 in the opening direction through the intermediary of a cam follower 33, shaft 34, gear segment 35, rotary vane servomotor 36, shaft 37 and operating lever 38. The cooler valve 20 and the heater valve 21 may be operated in a similar manner through servomotors, not shown on the drawing. The water separator 18 is arranged in a by-pass duct 24 and is brought into action when required by a

humidistat 39 arranged in the cabin and controlling the closing of a valve 25 provided in the main duct 19.

Since the refrigerator 17 is not required at altitudes exceeding 22,000 ft. (the mean change-speed altitude) it is preferred to provide an additional refrigerator by-pass valve 40 which is held open by an actuator 41 when the compressor speed control switch 13 is in the high speed setting.

The quantity of air passing through the compressor 6 is controlled in accordance with principles which will now be explained by a flow control device 42 acting on a throttle valve 43 in the compressor intake duct 44, on the refrigerator by-pass valve 22, and on a spill valve 45 arranged in a duct 46 branching from the main duct 19 between the heater 16 and the refrigerator 17.

Referring to Figure 9, the operating characteristics of a rotary vane compressor of the centrifugal or axial flow types may be represented by curves drawn using as non-dimensional co-ordinates compression ratio

20

25

P3

P2

and an inlet flow function $W\sqrt{T_2/P_2}$, in which:

W =Mass air flow per unit time.

P_2 =Absolute pressure at impeller intake (after any throttle valve that may be fitted).

T_2 =Absolute temperature at impeller intake.

P_3 =Absolute delivery pressure.

All pressures and temperatures referred to in this specification, with the exception of the Venturi throat pressure P_T referred to later, are total head values, i. e., they include the pressure and temperature equivalents of the velocity of the airstream.

On such a diagram a family of curves A, B, C may be drawn for each of which impeller tip speed divided by $\sqrt{T_2}$ is equal to a different constant value. It is found that such curves droop more and more steeply as the conditions of operation tend towards higher values of the inlet flow function, that is to say, the compression ratio falls and the machine becomes less and less efficient as a compressor as the flow increases. Working in the other direction, however, towards a smaller flow and a higher compression ratio a point is reached in each curve in which the operation of the machine becomes unstable, periodic fluctuations of mass flow and delivery pressure occurring which may be sufficiently violent to cause mechanical failure. This condition is known as "surge," and the curve D joining the surge points in the curves A, B, C, is termed the "surge line." To obtain maximum efficiency it is clearly desirable to operate the compressor under conditions approaching the surge line but sufficiently far from it to allow for unavoidable variations. It is found that if a family of curves are plotted such that the outlet flow functions $W\sqrt{T_3/P_3}$ =a constant, these lines lie roughly parallel to the surge line, and by suitably choosing the constant a line such as E is obtained which is suitable as an operating line in that it lies between the surge line D and the steeply drooping ends of the characteristic lines A, B, C. In the outlet flow function, T_3 is the absolute delivery temperature, which is constant for a given inlet temperature and impeller tip speed since it is known that the tem-

perature rise through the compressor varies directly as the square of the tip speed.

It can be shown, and has been experimentally confirmed, that the law of a Venturi system such as that shown in Figures 1 and 2 of the drawings is of the following form:

$$\frac{P_3 - P_T}{P_3} = \frac{P_D}{P_3} = K_1 \left(\frac{W \sqrt{T_3}}{P_3} \right)^2$$

Where P_3 = pressure at entry to venturi

P_T = throat pressure

P_D = differential pressure = $P_3 - P_T$

W and T_3 are the flow and temperature at entry to the venturi.

If, therefore, a venturi is fitted at the blower delivery, as shown in Figures 1 and 2, and some means of keeping P_D/P_3 constant is found, then $W\sqrt{T_3}/P_3$ will also be kept constant as is desired in order to satisfy the equation of the operating line E of Figure 9.

The means employed for this purpose are shown in Figure 2 and comprise an evacuated capsule 47 mounted in a closed box 48 connected by a conduit 49 to a pressure point at the inlet to the venturi 50, so that the capsule contracts in proportion to the delivery pressure P_3 . The moving end of the capsule 47 is connected to one arm of a lever 51 which is pivoted about an intermediate point 52 and the other arm of which is connected to one end of a capsule 53 the interior of which is connected by means of a sliding sleeve 54 and a conduit 55 to the throat of the venturi 50. The other end of the capsule 53 is connected by means of a pivoted lever 56 to a fluid pressure control valve 57 provided with two lands 58 and 59 which in the position of equilibrium close the ends of conduits 60 and 61 leading to a rotary vane type servomotor 62 which is the master actuator for the intake throttle valve 43 (Figure 1) as will be further described. A conduit 63 connected at 64 to a source of fluid under pressure (not shown) opens between the lands 58, 59, while conduits 65, 66 leading back to the operating fluid reservoir open outside the lands 58, 59, the arrangement being such that movement of the valve 57 in one direction or the other from the equilibrium position allows pressure fluid to enter the motor 62 on one side or the other of its rotating vane, while the chamber on the other side of the rotating vane is connected to the reservoir. Supposing now the delivery pressure P_3 remains constant, while the differential pressure P_D , which is the difference between the pressures in the conduits 49 and 55, increases due to increased air flow, it will be seen that the capsule 47 and hence the lever 51 remain unaffected while the capsule 53 tends to collapse thus moving the valve 57 towards the right. This movement initiates operation of the throttle master vane motor 62 in the direction to close the throttle 43 so that the flow falls. When the flow has fallen to its original value the valve 57 will have returned to its equilibrium position, thus the condition $P_D/P_3 =$ constant is satisfied in this case.

Suppose now the delivery pressure P_3 increases, due for example to the refrigerator being brought into action, the capsule 47 will contract, causing the valve 57 to move to the left and thereby initiating movement of the intake throttle valve 43 in the opening direction. The resulting increased flow will cause a corresponding increase in the differential pressure $P_3 - P_T$ so that the differential pressure capsule 53 contracts, moving the valve 57 back towards the right. It will therefore

be seen that displacement of the valve 57 towards the right is directly proportional to the differential pressure P_D and inversely proportional to the delivery pressure P_3 , and that the system 5 tends to return to a condition in which the valve 57 lies in the neutral (constant displacement) position in relation to the oil supply and return conduits. In other words the condition $P_D/P_3 =$ constant is again satisfied and the system can be 10 made to operate along the chosen operating line E provided the constants of the system are suitably chosen. These constants are the flexibility of the capsules 47 and 53, the proportions which the two arms of the lever 51 bear to each other, 15 and the value of P_D/P_3 produced by the Venturi system for the desired constant value of $W\sqrt{T_3}/P_3$.

It has already been shown that when the delivery pressure P_3 rises due to the refrigerator being brought into action, the inlet temperature, impeller tip speed and the cabin pressure being assumed constant, the air flow increases in proportion. This feature is an advantage rather than otherwise since it means that an equivalent 20 cooling effect can be obtained with a smaller reduction of temperature through the refrigerator. Moreover sufficient cool air is available to supply a system of air jets under the control of individual passengers. If, as is usual, the cabin ventilation 25 system includes means for mixing recirculated air with the fresh air from the supply plant, possibly at the rate of three times the normal minimum flow of fresh air, it will be seen that, if the flow of recirculated air remains the same, the proportional increase in the total air in circulation is 30 much smaller than that in the fresh air.

Considering now the effect of changes of compressor speed, for example when during pressurising at ground level without refrigeration the engine speed is increased from cruise to take off R. P. M., the inlet temperature T_2 remains constant and the delivery pressure is held constant by the cabin discharge valve, but the outlet temperature T_3 will increase, since the temperature rise through the compressor varies as the square of the speed. In these circumstances the operating line equation $W\sqrt{T_3}/P_3 = K$ shows that the airflow W decreases since T_3 increases. A similar condition arises when the compressor drive 45 changes from low to high gear at constant engine speed. The air supply plant must of course be designed to supply adequate air to the cabin under the minimum flow condition.

It has already been mentioned that when the aircraft is flying at an altitude such that the cabin differential pressure constitutes a substantial proportion of the compression the compressor 55 is capable of producing, there may not be sufficient reserve pressure available to run the refrigerator to the required output. In such a case the cabin thermostat 26 will control the actuator 28 to move the refrigerator cam 32 to its lowest position in relation to the follower 33 so that the shafts 34 and 37 turn in the directions of the arrows x and y respectively, which correspond to closing of the refrigerator by-pass valve 22. The delivery pressure should now rise to a value sufficient to cause an air flow through the system satisfying the operating line equation $W\sqrt{T_3}/P_3 = C$, 60 and the flow control 42 will move the throttle valve 43 towards a more open position in an endeavour to satisfy this demand. If the demand is not satisfied by the time the throttle valve 43 is 65 fully open the operating condition of the com-

pressor will move towards the surge line D, with consequent danger to the plant. To avoid this possibility provision is made, and will presently be described, whereby the master flow control actuator 62, after causing full opening of the throttle valve 43, overrides the temperature-responsive control of the refrigerator by-pass valve and moves this latter towards the open position. The demand of the cabin temperature control is thus made subordinate to that of the cabin pressure control.

Another case in which compressor surge might occur would be the partial or total blockage of the flow paths from the compressor to the cabin. For example such a blockage could occur in the case of an aircraft having two independent air supply plants if one compressor failed to change speed at the correct altitude and the aircraft continued to climb. When the low-speed ceiling of the blower running at low speed was reached, its non-return valve at entry to the cabin would close, because the other compressor running at higher speed would be able to maintain the correct cabin pressure, and the compressor running at low speed would go into surge. In such a case the flow control system would open the refrigerator by-pass valve 22 as described in the preceding paragraph, but this would not remove the blockage, and it is therefore necessary to open the spill valve 45 sufficiently to permit the required flow of air. The means by which these valve movements are carried out will now be described.

As will be seen from Figure 2 the flow control master actuator is arranged with its shaft in alignment with two rotary vane type servomotors. The servomotor 36 on the left operates the refrigerator by-pass valve 22 as already stated, while the servomotor 67 on the right operates the intake throttle valve 43 through gear segments 68, 69, shaft 70 and operating lever 71. Referring to Figure 3, which is a longitudinal section through the assembly of servomotors, the casing 72 of the master actuator 62 comprises an internal oil conduit 73 which, as seen from Figure 4, forms a continuation of the pressure fluid conduit 60 and opens through ports 74, 75 into chambers 76, 77. In a similar manner, the pressure fluid conduit 61 is connected to a conduit 78 in the casing 72 which opens into chambers 79, 80. When therefore the flow control valve 57 moves towards the right and fluid under pressure is admitted to the conduit 61, such fluid passes into the chambers 79, 80, while the opposite chambers 76, 77 are connected through the conduits 60, 65 to the reservoir. The vane 81 of the actuator therefore turns in a clockwise direction as seen in Figure 4, or in the direction of the arrow y as seen in Figure 2. Similarly, movement of the valve 57 to the left causes rotation of the vane 81 in an anti-clockwise direction.

The shaft of the vane 81 has an extension 82 constituting a pilot valve lying within the vane 83 of the servomotor 67 which operates the intake throttle valve 43. As seen in Figures 3, 5 and 6 the pilot valve 82 comprises a circumferential groove 84 from which diametrically opposite longitudinal feed grooves 85 extend part way towards the end of the valve. Spaced between the feed grooves are also a pair of discharge grooves 86 extending from the end of the valve part way towards the circumferential groove 84. The groove 84 communicates through ports 87 and a circumferential groove 88 in the shaft of the vane 83 of the servomotor 67 with a conduit 89 which is connected at 64 (Figure 2) to the source 75

of fluid under pressure. As shown in Figure 6, the vane 83 is provided with four ports 90, 91, 92, 93 which communicate with the four working chambers and are all shut off by the pilot valve 82 when the latter is in the relative position shown. If now the pilot valve is rotated in a clockwise direction as seen in Figure 6, fluid under pressure will pass from the grooves 85 through the ports 91 and 93 and will turn the vane 83 until it is once more in the same relative position with regard to the pilot valve. In other words, the vane 93 follows the movements of the pilot valve, and therefore of the master actuator vane 81 so long as its free movement is not prevented by engagement with the fixed abutments 94 and 95. In Figure 4, movement of the master actuator vane 81 from the line a a to the line b b corresponds to the opening movement of the intake throttle valve 43, the valve being actually moved by the servo vane 83 in moving from the line a' a' to the line b' b'. Further movement of the master actuator vane cannot be followed by the servo vane since it is stopped by the abutments 94 and 95.

The construction of the refrigerator by-pass valve servomotor 36 is similar to that of the servomotor 67 and requires no further explanation except to state that the pilot valve 96 carries a pinion 97 (Figures 2 and 3) meshing with the gear segment 25 of the temperature control system and also a pair of dogs 98 by which it is in lost-motion connection with corresponding dogs 99 on the master actuator vane 81 (see Figure 7, which is drawn to a larger scale than the other sections).

The sections in Figures 4, 6, 7 and 8 are drawn to show the relation of the ports during full refrigeration, that is to say the throttle valve servomotor vane 83 is at the end of its working stroke in the throttle open position, while the refrigeration by-pass valve servomotor vane 100 is at the end of its working stroke in the valve closed position. The master flow control actuator vane 81 has passed through part only of its working stroke, which is greater than that of the vane 83, and has brought its dogs 99 just into contact with the dogs 98 on the refrigerator pilot valve 96. If, when in this setting, the operating line equation is not satisfied, the master vane 81 will rotate further in an anti-clockwise direction owing to the flow control valve 57 remaining displaced to the left in Figure 2. The dogs 99 will therefore rotate the pilot valve 96 in the same direction, and the vane 100 will follow and will cause opening of the refrigerator by-pass valve 22. If stable flow conditions can be established by partial opening of the by-pass valve, the system becomes stabilized in that setting but if this is not attained by the time the valve has fully opened, corresponding to a line such as c c in Figure 8, a pair of complementary cams 101 on the shaft 37 come into action through the intermediary of cam follower 102, gear segment 103, differential gear 104, shaft 105 and operating lever 106 to open the spill valve 45. The travel of the vane 100 from the line c c to the line d d therefore corresponds to an extension of the movement of the refrigerator by-pass valve 22 beyond its fully open position and to the opening range of the spill valve 45. This arrangement is represented on Figure 1 by on override connection 107. The opening movement of the spill valve continues only until the operating line equation is satisfied.

A manual control 108 in the cabin controls an actuator 109 geared to the differential 104 so that the spill valve 45 may be deliberately set fully

open if desired, for example when starting up the plant or when testing it at ground level.

We claim:

1. A control system for regulating the output of a centrifugal or axial flow compressor comprising means to regulate the quantity of air entering the compressor, a Venturi system to which the compressor delivers, means responsive to the absolute delivery pressure of the compressor, means responsive to the differential pressure between the inlet and throat of the Venturi system and means controlled by said pressure-responsive means to adjust the air-regulator means to vary the quantity of air passing through the compressor in such a way that the ratio of the Venturi differential pressure to the compressor delivery pressure is maintained constant.

2. A control system for regulating the output of a centrifugal or axial flow compressor comprising a throttle valve on the intake side of the compressor, a Venturi system on the output side of the compressor, a capsule responsive to the absolute delivery pressure of the compressor, a capsule responsive both to the pressure at the inlet and at the throat of the venturi, a servo-system for adjusting the throttle valve and means applying the capsule adjustments to the servo-system whereby the throttle valve is adjusted to vary the quantity of air passing through the compressor in such a way that the ratio of the Venturi differential pressure to the compressor delivery pressure is maintained constant.

3. A control system as claimed in claim 2 in which the adjustments of one capsule due to variations in pressure are applied to move the other capsule and adjustments of the latter due to the first capsule and to variations in pressure are applied to the servo system.

4. A control system as claimed in claim 3 in which the capsules lie on opposite sides of, and are coupled to opposite ends of, a first-class lever, the end of one capsule remote from the lever being fixed and the end of the other capsule remote from the lever being connected to the servo system.

5. A control system as claimed in claim 3 in which the fixed end of the first capsule is manually adjustable to move the capsule and rock the lever.

6. A control system as claimed in claim 2, wherein the servo system opens, over a first part of its range, the throttle valve to its full extent and over a further part of its range, it opens a valve on the delivery side of the compressor whereby a further rise of delivery pressure at the existing compressor speed is opposed.

7. A control system as claimed in claim 6 in which air is delivered by the compressor to an aircraft cabin and there is a refrigerator unit run by the compressed air to cool the air prior to its entering the cabin, a by-pass for the air being provided around the refrigerator unit with a valve to regulate the quantity of air passing through and around the unit, said by-pass valve being opened over the further part of the range of the servo system whereby after full opening of the throttle valve a further rise of delivery pressure at the existing compressor speed is opposed.

8. A control system as claimed in claim 6 in which a spill valve is provided to discharge air from the compressor to atmosphere, said valve being opened over the further part of the range of the servo system whereby after full opening of the throttle valve a further rise of delivery

pressure at the existing compressor speed is opposed.

9. A control system as claimed in claim 7 wherein the servo system first opens the refrigerator by-pass valve and then the spill valve.

10. A control system as claimed in claim 7 wherein the refrigerator by-pass valve is normally regulated by a temperature control in the cabin and the servo system over-rides said control to open the by-pass valve when, with a fully open throttle, the pressure requirements cannot be met.

11. A control system as claimed in claim 7, wherein there is means to by-pass air around the refrigerator unit when the aircraft is flying above a predetermined altitude.

12. A control system as claimed in claim 11 in which there is an additional by-pass to convey air around the refrigerator unit, said by-pass having a valve which is regulated by a barometric capsule to open during ascent at the predetermined altitude.

13. A control system as claimed in claim 8, in which the spill valve is manually adjustable independently of the servo system.

14. A control system as claimed in claim 2 wherein air is delivered by the compressor to an aircraft cabin and the compressor is driven through variable speed gearing, changes in speed ratio being solely dependent on altitude.

15. A control system as claimed in claim 14 in which a given speed ratio is engaged at a certain altitude during ascent of the aircraft and is disengaged at a lower altitude during descent of the aircraft.

16. A control system as claimed in claim 2 wherein the servo system comprises a reciprocating servo-valve under the control of the capsules, a rotary vane master servo-motor regulated by the servo-valve, a rotary vane servomotor to adjust the throttle valve and a rotary valve of which the vane of the throttle motor forms one element and of which the other element is adjusted by the master motor, opening of the rotary valve on operation of the master motor to a certain extent bringing the throttle motor into operation to adjust the throttle and close the rotary valve when the throttle motor has been operated to a corresponding extent.

17. A control system as claimed in claim 16 in which the range of operation of the master motor is greater than the range of operation of the throttle motor and there is a second rotary valve which is adjustable by the master motor to operate a rotary-vane servomotor which adjusts the refrigerator by-pass valve, a lost motion device in the drive from the master motor to the second rotary valve ensuring that the refrigerator servomotor is brought into operation by the master motor only after the throttle valve is fully open.

18. A control system as claimed in claim 17 wherein the rotary valve of the refrigerator servomotor is normally adjustable by an actuator, the operation of which is regulated by said temperature control.

19. A control system as claimed in claim 17 in which the refrigerator servomotor is adapted to adjust the spill valve through the agency of a cam mechanism.

20. A compression plant comprising a casing, a driven rotary impeller therein, control means comprising a flow control device for varying the pressure of the working medium at the inlet to the impeller, means comprising a flow metering

device positioned in the path of the working medium and responsive to changes in volume flow through the impeller, and means comprising a contracting mechanism responsive to changes in the pressure of the working medium at the outlet from the impeller, said flow control device being actuated by said second and third means to vary the inlet pressure in a manner such that the algebraic sum of a control action derived from the second means and of a control action derived from the third means is maintained equal to zero, said first control action being in the sense to keep the volume flow constant and said second control action being in the sense to vary the volume flow in the same sense as the changes in outlet pressure.

21. A compressor plant as claimed in claim 20 in which the second control action is derived from

means responsive to changes in the total head pressure at the outlet of the impeller.
